(57) **CLAIM**

The ornamental design for a handle cover, as shown and described.

DESCRIPTION

FIG. 1 illustrates a perspective view of a handle cover; FIG. 2 illustrates a front view of the handle cover of FIG. 1; FIG. 3 illustrates a back view of the handle cover of FIG. 1; FIG. 4 illustrates a left side view of the handle cover of FIG. 1; FIG. 5 illustrates a right side view of the handle cover of FIG. 1; FIG. 6 illustrates a top view of the handle cover of FIG. 1; and, FIG. 7 illustrates a bottom view of the handle cover of FIG. 1.

The broken lines in the figures represent stitching that does not form part of the claimed design. The broken lines illustrating features in FIG. 7 represent portions of the article which form no part of the claimed design.

1 Claim, 4 Drawing Sheets
